UNITED STATES PATENT OFFICE.

VICTOR H. JENNINGS, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

POCKETED CARRIER.

1,282,695.

Specification of Letters Patent. Patented Oct. 22, 1918.

Application filed October 6, 1917. Serial No. 195,155.

To all whom it may concern:

Be it known that I, VICTOR H. JENNINGS, a citizen of the United States, residing at Worcester, in the county of Worcester, State 5 of Massachusetts, have invented a certain new and useful Improvement in Pocketed Carriers, of which the following is a specification, reference being had therein to the accompanying drawings.

10 The invention has relation to cartridge-carriers and other pocketed carriers of woven material on the order of those which constitute elements of military equipment and the like. More particularly, it has reference to carriers of the class comprising a pocket-piece woven with one or more pockets or pouches and combined with a backing-piece. It is useful in the case of carriers in which the backing is a long cover-web that is fastened across its lower end to the bottom of the pocket-piece, and across its middle to the top of the pocket-piece, so that the portion thereof between the two lines of fastenings forms a loop for transverse insertion of 20 the supporting-belt while the upper portion 25 constitutes a pocket-cover or flap.

The general objects of the invention are to improve the character, construction, and appearance of carriers of the said class, and 30 facilitate and expedite the manufacture thereof.

Embodiments of the features of the invention are shown in the drawings, in which latter

35 Figure 1 is an isometric oblique view of a carrier for magazines for automatic pistols, embodying the said features.

Figs. 2 and 3 are views in cross-section on lines 2, 2, and 3, 3, respectively, of Fig. 1.

40 Fig. 4 is an isometric oblique view of a pocket-piece such as employed as a part of the magazine-carrier of Figs. 1 to 3, looking at the front thereof.

Fig. 5 is a view in section on line 5, 5, of 45 Fig. 4.

Fig. 6 is an isometric oblique view looking at the back of the said pocket-piece.

The pocketed carrier of Figs. 1 to 3 is furnished with two pockets 1, 1, designed to 50 receive magazines for automatic pistols. It comprises a pocket-piece which is woven with such pockets, and a backing 2, of woven material to which the said pocket-piece is fastened. The number of pockets may vary

in practice, and in different embodiments of 55 the invention the proportions of the pocket or pockets may vary according to the nature, etc., of the article or articles intended to be received therein. The application of the fastenings by which the pocket piece and 60 backing are secured to each other may vary.

The illustrated carrier is adapted to be slipped upon a supporting-belt. To provide for such mode of applying the carrier to the supporting-belt the backing 2 is of a 65 length somewhat exceeding the height of the pocket-piece and is fastened only across its lower end, as by a transverse line of stitches 3, to the bottom of the pocket-piece, and across its middle, as by transverse lines of 70 stitches 4, 4, to the top of the pocket-piece, so that the portion of the backing between the two transverse lines of fastening forms a loop for transverse insertion of the supporting-belt. The upper portion of the 75 backing 2 constitutes in this embodiment of the invention a pocket-cover or flap 5, which is adapted to be folded forward over the tops of the pockets 1, 1, and down against the fronts of said pockets. At 6, 6, and 7, 7, 80 are coacting fastener-members which are attached to the free end of the pocket-cover or flap and to the fronts of the pockets, to keep the cover or flap securely closed down in place, as usual.

85 One characteristic feature of a carrier embodying the invention is the upwardly-extending flange 8 rising from the back of the pocket-piece above the pocket-top, and with which the upper lines of stitches 4, 4, are engaged for the purpose of fastening the top of the pocket-piece to the middle portion of the length of the cover-piece. Such lines of fastenings are located above the pocket-top.

90 The pocket-piece has the front wall 9 and back wall 10 of the pockets thereof united in the weaving at 11 and 12 at the lateral sides of the pockets, as shown to best advantage in the views of the pocket-piece in Figs. 4 and 5. At the lateral sides of the pocket or pockets of the pocket-piece, the latter, as woven, has side-wings 13, 13, Figs. 2 and 4 to 6, beyond the side-joinings 12, 12. These side-wings are folded around and secured at the back of the pocket or pockets, as 95 shown in Fig. 2, before the attachment of the pocket-piece and backing to each other, so that the folded side-wings are covered by 100 105

the backing in the finished carrier. The mode of fastening the side-wings in place at the back of the pocket or pockets may vary in practice. Preferably their free edges are butted together and the butt-joint is covered by a tape 14, Fig. 2, fastened to the side-wings by lines of stitches 15, 15, along its side-edges. This mode of fastening the folded side-wings in place, and binding the joint, covers in the raw or cut edges and provides for easy insertion of the end of the supporting-belt through the opening of the loop, and ready slipping of the belt through the loop.

15 Preferably, though not necessarily in all instances, the side-wings 13, 13, of the pocket-piece are woven thinner than the portions of the pocket-piece at 11 and 12, 12, where the front and back walls of the 20 pockets are joined in the weaving. This reduction in thickness lessens the amount of material that is turned in at the back of the pocket-piece. To produce the side-wings of reduced thickness, the warp-threads 16, 16, 25 Figs. 5 and 6, of one of the pocket-walls, in this case those of the back walls, are floated without interweaving with weft-threads after the pocket-walls have been joined together at 12, 12. Thereby the said wall is 30 discontinued beyond the side-joinings of the pocket-walls. Preferably the said warp-threads are caused to float at the back surface of the pocket-piece, as in Fig. 6, and after the weaving are cut away.

35 The upwardly-extending flange 8 of the pocket-piece is constituted of a supplemental web-portion that is integral with the back pocket-wall at the pocket-tops, with the side-joinings 11 and 12, 12, and also with 40 the lateral continuations constituting the side-wings 13, 13. In order that the said supplemental web-portion may be woven integral with the back wall of a pocket, or of each of the two pockets of the form of carrier illustrated in the drawing, and with the lateral continuations of the front wall, alone, constituting the side-wings, the warp threads of said supplemental web-portion are controlled for shed-forming purposes 45 in the loom by a set of harnesses additional to those employed for forming the sheds in the warp-threads of the other portions of the pocket-piece.

50 The supplemental web-portion constituting the flange 8 is woven of sufficient length to provide for turning the end-portions of the said flange to the back, so that the line or lines of fastenings 4 engaging with the flange also engage with the inturned ends of 55 the flange. Thereby a better finish is secured, and the upper corners of the pocket-piece are more effectually reinforced.

By providing the pocket-piece with a flange rising above the pocket-tops and securing the pocket-piece to the backing by

means of fastenings engaging with the said flange, a better carrier is produced, and the serious inconvenience of applying the fastenings to the back wall of the pocket below the pocket-top is obviated.

What is claimed as the invention is,—

1. A pocketed carrier for detachable application to a supporting-belt, comprising a pocket-piece woven with opposite side-wings which are folded around and secured at the back, and a cover-web which is fastened across the middle of its length to the top of the pocket-piece and across the lower end to the lower end of the pocket so that the upper portion of said cover-web constitutes a flexible pocket-cover or flap and the lower portion thereof constitutes a loop that is separable from the back of the pocket between the upper and lower fastenings to permit the said supporting-belt to be passed through transversely, said pocket-piece woven with a narrow flange projecting above the top of the pocket and with which the upper fastenings are engaged above the top of the pocket.

2. A pocketed carrier of woven material adapted to be slipped upon a supporting-belt, comprising a pocket-piece woven with side-wings that are turned to the back and secured, and a long cover-web that is fastened across its lower end to the bottom of the pocket-piece and across its middle to the pocket-piece above the top of the pocket, so that the supporting-belt may be slipped transversely through between the lower portion of the cover-web and the inturned side-wings while the upper portion of the cover-web constitutes a pocket-cover or flap, said pocket-piece also woven with a flange rising above the pocket-top and having the ends of said flange turned to the back and the said upper line of fastenings engaged with the flange and its inturned ends.

3. A pocketed carrier comprising a backing, and a woven pocket-piece having the front and back walls of the pocket thereof joined in the weaving at the lateral sides of the pocket, with lateral continuations of diminished thickness beyond the side-joinings of said pocket-walls, the said pocket-piece also woven with a flange projecting above the mouth of the pocket consisting of a supplemental web-portion that is integral with the back pocket-wall at the pocket-top and also with the said lateral continuations and having said lateral continuations and the ends of said flange bent around and secured at the back, and fastenings engaging with said flange externally of the pocket and securing the same to the said backing.

4. A pocketed carrier comprising a backing, and a woven pocket-piece having the front and back walls of the pocket thereof united in the weaving at the lateral sides of the pocket, with lateral continuations of

the pocket-front beyond the side-joinings of said pocket-walls, and with one of the walls discontinued beyond the places of union of the two walls to reduce the thickness of said 5 lateral continuations, the said pocket-piece woven with a flange projecting above the mouth of the pocket, consisting of a supplemental web-portion that is integral with the back pocket-wall at the pocket-top, and 10 also with the said lateral continuations of the pocket-front and having said lateral continuations and the ends of said flange bent around and secured at the back, and fastenings engaging with said flange externally of 15 the pocket and securing the same to the backing.

5. A pocketed carrier comprising a backing, and a woven pocket-piece attached thereto having the front and back walls of the pocket or pockets thereof joined in the 20 weaving at the lateral sides of the pocket, with lateral continuations of diminished thickness beyond the side-joinings of said pocket-walls, and with said lateral continuations bent around and secured at the back 25 of the pocket-piece.

In testimony whereof I affix my signature in presence of two witnesses.

VICTOR H. JENNINGS.
